SHOE

Application filed June 25, 1928. Serial No. 287,949.

The present invention relates to shoes, and more particularly to bottom reinforcements therefor.

Shoe bottoms should be pliant longitudinally and rigid laterally. That is, the outsole should bend freely about lateral axes but should be stiff enough to resist bending about longitudinal axes. Outsoles which are pliant longitudinally and rigid laterally are flexible enough to make walking easy and are stiff enough to prevent distortion of the insole due to the tendency of the outsole to bend laterally when the tread surface of the outsole engages irregularities in a rough surface. Outsoles, whether composed of leather, rubber or composition, are, however, subject to uneven wear. This results in discomfort long before the shoe is worn out. In walking on a rough surface the weakened portion of the worn outsole is forced upwardly by the unevenness of the rough surfaces so that the pressure therefrom is localized in a spot on the foot. It has been proposed heretofore to reinforce the shoe or the outsole therefor with a layer of woven wire fabric but these layers if made flexible enough to permit the outsole to flex freely in walking were not stiff enough to resist bending of the outsole laterally and if made rigid enough to resist the lateral bending of the outsole prevented its flexing longitudinally.

The principal object of the present invention is to provide a shoe or a part thereof with a reinforcement which will permit the flexing of the outsole longitudinally and which will resist the bending of the outsole laterally.

To the accomplishment of this object, the invention comprises the features and combinations of parts fully set forth hereinafter, the advantages of which will be readily understood by those skilled in the art.

The various features of the present invention will be readily understood from an inspection of the accompanying drawings illustrating the best forms of the invention at present known to the inventor, in which:

Figure 1 is an elevation, partly in section, of a welt shoe embodying the features of the present invention;

Fig. 2 is a plan of the bottom of a welt shoe before receiving the outsole, the warp and weft strands of wire being shown diagrammatically only to indicate that each course in the warp comprises a plurality of strands while each course in the weft comprises a single strand;

Fig. 3 is a detail plan of the reinforcement; Fig. 4 is an enlarged detail perspective of the reinforcement; and

Fig. 5 is a sectional elevation of the fore-part of a rubber or composition outsole having the reinforcement embedded therein.

In the embodiment of the invention illustrated in Figs. 1 and 2 an upper 6, insole 7 and welt 8 are secured together by an inseam 9 in the usual manner. A filler 10, which may be the common plastic cork composition or a fitted unitary piece of material, is applied to the insole 7 within the sewing rib 11 thereof. Before the outsole 12 is secured to the welt 8 by an outseam 13, the shoe is reinforced by a layer of woven wire fabric 14 located adjacent the unexposed surface of the outsole in the finished shoe.

As shown particularly in Fig. 2 the fabric 14 is composed of courses of warp and weft strands of wire, the warp extending longitudinally of the shoe and the weft extending laterally of the shoe. Each course in the warp comprises three strands of wire 15 of relatively small gauge. Each course in the weft comprises a single strand of wire 16 of relatively large gauge. As shown in Fig. 2, the warp courses may be spaced farther apart than the weft courses.

The fabric 14 is pliant and may readily be bent about the axes of the stiffer weft strands 16 but is quite stiff when attempting to bend it about the axes of the light warp strands. Stated in another way, the fabric 14 flexes freely when the outsole 12 is flexed longitudinally, but resists the tendency for the outsole to bend laterally. With this construction, even after a considerable amount of wear of the outsole, the foot-engaging surface of the insole will be even and comfortable even when walking on a rough surface as the reinforcement prevents distortion of

the weakened portions of the outsole, thus preserving the smoothness of the insole.

The layer 14 is died out of the woven wire fabric to fit within the sewing rib 11 on the insole. The strands 16 are made stiff enough to resist bending while the strands 15 are made light enough to bend readily. When a plastic filler is used in the welt shoe the pressure of the sole laying operation is sufficient to bond the uneven surface of the woven wire fabric to the filler and thus provide against the displacement of the fabric. When a unitary piece of filling material, such as prepared felt or fibre, is used, the strands 16, for example, in the woven fabric may be roughened or upset at intervals to provide spurs for gripping the filler material under the sole-laying pressure.

As shown in Fig. 5 the died out layer of woven wire fabric 14 may be embedded in a rubber or composition outsole 17 during the molding thereof. The layer 14 is located adjacent the unexposed surface of the outsole as far from the tread surface 18 as is practicable in order to provide for the maximum wear of the outsole 17. The warp and weft strands are arranged longitudinally and laterally of the outsole 18, respectively, in order to permit free flexing of the outsole longitudinally when applied to a shoe and at the same time resist the tendency of the outsole, even when worn in spots, to be distorted. The fabric 14 is spaced from the peripheral edge of the outsole to clear the line of the outsole 13.

It is within the scope of the invention to apply the novel reinforcement to various types of shoes other than the welt shoe shown in the drawing for illustrative purposes. Those skilled in the art will understand its application from the foregoing description and it need only be added that when used in canvas footwear such as sneakers, or footwear wholly of rubber, the reinforcement may still be applied between the insole and outsole, when present, or molded into the outsole in the manner illustrated by Fig. 5.

The nature and scope of the invention having been indicated, and its preferred embodiment having been specifically described, what is claimed as new, is:—

1. In a shoe, the combination with an outsole, of a reinforcement comprising woven material, having each course of its warp composed of a plurality of wires of relatively small gauge and each course of its weft composed of a single wire stiffer than the warp wire, located in the shoe adjacent the unexposed surface of the outsole.

2. In a shoe, the combination with an outsole, of a reinforcement comprising woven material, having the courses of its warp spaced farther apart than the courses of its weft, each course of the warp being composed of a plurality of wires of relatively small

gauge and each course of the weft being composed of a single wire stiffer than the warp wire, located in the shoe adjacent the unexposed surface of the outsole.

3. A shoe construction including an outsole reinforced remote from its tread surface with a layer of woven wire fabric having a weft of sufficient stiffness to resist lateral flexure of the outsole and a pliant warp and arranged in the shoe with its warp extending longitudinally of said outsole.

4. A shoe having, in combination, an upper, an insole, an outsole, and a layer of woven wire interposed between the insole and the outsole, said layer being so constructed as to resist flexure in one direction while permitting flexure in the other direction and arranged on the shoe to flex freely with the outsole when under pressure while on the foot of the wearer.

5. A shoe having, in combination, an upper, an insole, an outsole, and a layer of woven wire interposed between the insole and the outsole, said layer being flexible about axes laterally of the shoe and more rigid under forces tending to bend it about axes longitudinally of the shoe.

6. A welt shoe construction including a pliable filler interposed throughout the forepart between the insole and outsole, and a layer of woven wire embedded in said filler woven in a manner to stiffen the shoe bottom and prevent distortion laterally but completely permit all longitudinal flexures required when on the foot of the wearer.

7. A shoe construction including an outsole stiffened to prevent lateral distortion thereof by a layer of woven wire fabric that is wholly pliant when bent about the axes of one series of woven strands but which will resist flexure when attempting to bend it about its other series of woven strands, said wires lying in the shoe with the stiffer strands extending across the outsole to hold it flat laterally and preserve the smoothness of its inner face, and with the pliant strands extending lengthwise of the outsole to permit longitudinal flexure thereof.

In testimony whereof I affix my signature.
